(57) **CLAIM**

The ornamental design for a syringe accessory as shown and described.

DESCRIPTION

FIG. 1 is a front perspective view of a syringe accessory of our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings illustrate portions of the syringe accessory that form no part of the claimed design.

1 Claim, 4 Drawing Sheets
